UNITED STATES PATENT OFFICE.

THOMAS S. BLAIR, JR., OF CHICAGO, ILLINOIS, ASSIGNOR TO BLAIR ENGINEERING COMPANY, OF NEW YORK, N. Y., A CORPORATION OF NEW YORK.

OPEN-HEARTH FURNACE.

1,245,555.

Specification of Letters Patent.

Patented Nov. 6, 1917.

Application filed July 20, 1917. Serial No. 181,684.

To all whom it may concern:

Be it known that I, THOMAS S. BLAIR, Jr., a citizen of the United States, residing at 343 South Dearborn street, Chicago, in the 5 county of Cook and State of Illinois, have invented a new and useful Improvement in Open-Hearth Furnaces, of which the following is a specification.

My invention relates to certain new and 10 useful improvements in open hearth furnaces and is fully described and explained in the specification and shown in the accompanying drawings, in which:

Figure 1 is a central longitudinal section 15 on the line 1 of Fig. 3 through the end of an open hearth furnace; Fig. 2 is a section on the line 2 of Fig. 1 through the furnace setting showing the gas port covering and its associated parts in plan, a portion there- 20 of being broken away to show the structure underneath; Fig. 3 is an end view of the furnace; Fig. 4 is a perspective view of the gas port covering, its connections and the bulk-head construction; and Fig. 5 is a hori- 25 zontal section on the line 5 5 of Fig. 1.

Referring to the drawings, 6 is the gas 30 port covering made in accordance with my application filed September 12, 1916, Serial No. 119,689. The remainder of the furnace 35 is of a typical form, such as that described in the aforesaid application and requires no detailed description. 7 is a gas down take and at the upper end of the down take, and immediately below the entrance of the gas 40 port thereto, is a water cooled bulk-head 8 of the form also shown, described and claimed in my aforesaid application.

In the operation of the furnace in said 45 application it has been found that not only does the slag coming back through the gas port accumulate upon the bulk-head as 50 therein set forth, so as to protect the surface thereof and also prevent undue chilling, but at the extreme upper end of the bulk-head slag often accumulates in a lump 55 of considerable size so that after a period of use the lump is big enough to somewhat throttle the down-take and it is then necessary to break off the lump. In common 60 practice with the device of the aforesaid application it has been customary to line the bulk-head with an initial thin layer of clay brick, and sometimes in breaking off this lump the whole lining has come off with 65 it and fallen into the slag pocket. While

these matters are not of great importance, they nevertheless result in some inconvenience, and it has been discovered that the structure herein shown completely avoids the accumulation of any slag lump and yet 60 keeps the inner surface of the bulk-head completely protected.

In the present structure I run from front to back along the furnace and just inside the bulk-head 8 a series of flattened pipes 9. 65 These pipes in practice have a major diameter of about 6 inches and the major diameter inclines slightly upward and inward from the bulk-head surface. The pipes extend through the furnace from the front to 70 back walls, or in the case of a "dog-house" type of furnace like that illustrated from the front to back walls of the gas down take. The space between the pipes 9 is filled with 75 bodies of chrome ore 10. Water is circulated through the pipes 9 in order to make them relatively permanent, and prevent their destruction by heat.

It is found in practice that a furnace of this structure runs indefinitely without any 80 slag accumulation and with no appreciable depreciation of the chrome ore body. I do not pretend to explain the reason for this action. It is possible that the slag really does accumulate until of sufficient thickness 85 to break away a small volume of the chrome ore so that successive fresh surfaces are exposed from time to time. However this may be it is a fact that at no time is there either a noticeable accumulation of 90 slag or an appreciable disappearance of the chrome ore.

For the purpose of passing water through the ore supporting pipes 9, each is provided with an intake pipe 11 and an outlet 12. 95 Water enters the intake pipe 11 from a header 13 to which it may be supplied by any appropriate means as by a stream running into a funnel-shaped opening in the top of the header. The outlet pipes 12 are all 100 carried up and discharge into the port covering.

I realize that considerable variation is possible in the details of this construction without departing from the spirit of my invention; therefore, I do not intend to limit myself to the specific form herein shown and described except as pointed out in the following claims, in which it is my intention 105 to claim all the novelty inherent in the con- 110

struction as broadly as is permitted by the state of the art.

What I claim as new and desire to secure by Letters Patent is—

- 5 1. In an open hearth furnace walls forming a gas port and a down-take communicating therewith, a chrome ore facing in the upper part of the end wall of the gas down-take immediately below the entrance of the gas port thereto, and means for maintaining said facing in position.
- 10 2. In an open hearth furnace walls forming a gas port and a down-take communicating therewith, a chrome ore facing in the upper part of the end wall of the gas down-take immediately below the entrance of the gas port thereto, and means for maintaining said facing in position said means consisting of a series of water cooled shelves upon which sections of the facing rest.
- 15 3. In an open hearth furnace walls forming a gas port and a down-take communicating therewith, a water cooled bulk-head in the upper part of the end wall of the down-take immediately below the entrance of the gas port thereto, a chrome ore facing on the bulk-head, and means for maintaining the facing in position said means consisting of a series of water cooled shelves upon which sections of the facing rest.
- 20 4. In an open hearth furnace walls forming a gas port and a down-take communicating therewith, a chrome ore facing in the upper part of the end wall of the gas down-take immediately below the entrance of the gas port thereto, and means for maintaining said facing in position said means consisting of a series of water cooled shelves upon which sections of the facing rest.
- 25 5. In an open hearth furnace walls forming a gas port and a down-take communicating therewith, a water cooled bulk-head in the upper part of the end wall of the down-take immediately below the entrance of the gas port thereto and inclining upward and outward, a chrome ore facing on the bulk-head, and means for maintaining the facing in position, said means consisting of a series of water cooled shelves upon which sections of the facing rest.
- 30 6. In an open hearth furnace walls forming a gas port and a down-take communicating therewith, a water cooled bulk-head in the upper part of the end wall of the down-take immediately below the entrance of the gas port thereto and inclining upward and outward, a chrome ore facing on the bulk-head, and means for maintaining the facing in position said means consisting of a series of water cooled shelves upon which sections of the facing rest.
- 35 7. In an open hearth furnace walls forming a gas port and a down-take communicating therewith, a water cooled bulk-head in the upper part of the end wall of the down-take immediately below the entrance of the gas port thereto and inclining upward and outward, a chrome ore facing on the bulk-head, and means for maintaining the facing in position said means consisting of a series of water cooled shelves upon which sections of the facing rest.

of the gas port thereto and inclining upward and outward, and means for maintaining said facing in position.

5. In an open hearth furnace walls forming a gas port and a down-take communicating therewith, a chrome ore facing in the upper part of the end wall of the gas down-take immediately below the entrance of the gas port thereto and inclining upward and outward, and means for maintaining said facing in position, said means consisting of a series of water cooled shelves upon which sections of the facing rest.

6. In an open hearth furnace walls forming a gas port and a down-take communicating therewith, a water cooled bulk-head in the upper part of the end wall of the down-take immediately below the entrance of the gas port thereto and inclining upward and outward, a chrome ore facing on the bulk-head, and means for maintaining the facing in position.

7. In an open hearth furnace walls forming a gas port and a down-take communicating therewith, a water cooled bulk-head in the upper part of the end wall of the down-take immediately below the entrance of the gas port thereto and inclining upward and outward, a chrome ore facing on the bulk-head, and means for maintaining the facing in position said means consisting of a series of water cooled shelves upon which sections of the facing rest.

THOMAS S. BLAIR, JR.
